UNITED STATES PATENT OFFICE.

FRANK S. VERNON, OF JAMESTOWN, NEW YORK.

SHEET-METAL SHAPING AND BENDING MACHINE.

1,233,732.

Specification of Letters Patent. Patented July 17, 1917.

Application filed February 1, 1915. Serial No. 5,372.

To all whom it may concern:

Be it known that I, FRANK S. VERNON, a citizen of the United States, residing at the city of Jamestown, in the county of Chautauqua and State of New York, have invented certain new and useful Improvements in Sheet-Metal Shaping and Bending Machines, of which the following, taken in connection with the accompanying drawings, is

10 a specification.

The invention relates to certain improvements in machines for bending and shaping metal sheets into tubular or open-sided molding; and the object of my improvement 15 is to provide a progressive series of pairs of rolls to shape and bend and thereby form the sheet metal into the desired pattern or shape and placing rigid shaping and bending and guiding dies between the consecutive 20 pairs of rolls to act simultaneously as guides and shaping and bending dies and to provide said fixed dies with rollers therein to aid the sheet metal stock in passing through said fixed dies and at the same time 25 to aid in shaping and bending said stock; and the invention consists in the novel features and combinations hereinafter set forth and claimed.

In the drawings, Figure 1 is a perspective view of the connective gear side of the machine with the strip of sheet metal passing through the dies shaping and bending it to the desired form; Fig. 2 is a side elevation of the opposite side of the machine from 30 that shown in Fig. 1; and Fig. 3 is a top plan view of the machine showing the fixed dies between the roller dies.

Fig. 4 is a perspective view of the first 40 one of the series of fixed dies removed from the machine and having the largest opening therethrough for guiding and shaping and bending the sheet metal strip to the desired shape; Fig. 5 is a perspective view of the second fixed die of the series, roller dies being placed between the fixed dies; Fig. 6 is 45 a perspective view of the next fixed die, each of the three dies shown in Figs. 4, 5 and 6 being provided with rollers for aiding the stock through said fixed dies; and Fig. 7 is 50 an elevation of the central portion of the die shown in Fig. 6, showing the relation of the spool shaped roller to the tongue of the die, which extends into the same with tongue and groove effect to aid in shaping 55 the sheet metal. Fig. 8 is a perspective view of the fourth fixed die of the series; and

Fig. 9 is a perspective view of the last of the fixed dies in the machine shown, each of the open dies 8 and 9 being shaped to accomplish a certain portion of the work of 60 shaping and bending the sheet metal strip. The two dies shown in Figs. 8 and 9 are open topped instead of closed dies as shown in Figs. 4, 5 and 6, and do not require the aid of the roller.

Fig. 10 is a top plan view of the machine with the sheet of metal passing therethrough showing the gradual shaping and bending of the sheet metal until it issues in the desired form, as shown in Fig. 11, a 70 perspective view of the frame side of a screen with a channel in the outer edge and in the side of the inner edge and the edges of the sheet metal strip interlapped in the inner channel and said inner channel enlarged inwardly.

Fig. 12 is a perspective view of one of the top plates of the fixed dies removed therefrom and inverted showing the assisting roller thereon supported at each end by an 80 angular plates which are attached to the under side of the top plate.

Fig. 13 is a detail sectional view of the spaced blocks of the frame 13 and a top plan view of the journal blocks therebetween and portions of the roller dies which are journaled in said journal blocks, showing said journal blocks slidably held against said spaced blocks by the roller dies.

Fig. 14 is a sectional view through the 90 journal and journal block of the gear side of the frame showing the removable attachment of the piece of the journal to said roller die and the gear on the outer end of said piece. Figs. 15 to 25, inclusive show in 95 cross section, the strip in the several bending steps as it merges from the numerous roller and fixed dies; and Fig. 26 is an end elevation of the finished molding.

Like numerals of reference refer to corresponding parts in the several views.

The machine is shown with a strong rigid upright frame comprising a bed 10 having the leg supports 11 attached thereto.

The parallel top frames 12 and 13 are attached to the opposite sides of the top of the bed 10 by means of dovetail-shaped projections 16 which are received in dovetail-shaped openings in the sides of the lower ends of the series of metal blocks 14 that 105 make up the frames 12 and 13 by means of the connecting top rails 15 which rails are

attached to the upper ends of the blocks 14 by means of screw-bolts 17.

The metal blocks 14 are held a spaced distance apart by means of the dovetail-shaped projections 16. In each pair of the roller dies 26 one is mounted above the other in journal blocks 18 and 19 having coil springs 20 therebetween and an adjusting screw 21 bearing on the top of the block 18 through the top rail 15 with set nuts for holding said adjusting screw 21 firmly in position. This arrangement permits the blocks 18 to resiliently move to and from blocks 19 except as limited by the set screws 21, the blocks 18 and 19 being slidably mounted in the opening between the blocks 14, as shown in Figs. 2 and 13.

The journal blocks 18 are formed as shown in Figs. 2 and 13 with flanged exterior 20 tensions on each vertical inner side which bear against the blocks 14 of the frame 13. The journal blocks 19 for the lower rolls are formed in substantially the same shape as blocks 18 and rest upon the dovetail-shaped projections 16 on the bed plate 10. The journal blocks 18 and 19 preferably have small openings not shown in their upper and under sides to receive the ends of the coil springs 20 so that said coil springs 30 will invariably work freely in line between said journal blocks. The journal blocks in the frame 12 upon which the gears 22 are mounted are the same as those in frame 13, but are preferably mounted so that the roller dies may be removably inserted in said journal blocks without the removal of the gears 22 from the journal.

In order to attain the easy removal of the roller dies and the insertion of other 40 roller dies, the journal blocks 18 and 19 on the side bearing the intermeshing driving gears 22, are provided with a short socket shaft 23 to which the gear 22 is keyed, a socket 24 being provided on the inner end 45 of the short shaft 23 having a key-way 25, and the roller die 26 is provided with a short shaft end 27 which has a feather key thereon fitting into the key-way 25. It is now apparent that when it is desired to change 50 the roller dies 26, the top rail 15 is removed permitting the journal blocks 18 and 19 to be raised and removed, with the gear 22 and socket shaft 23 attached thereto, from the end of the shaft 24, which socket shaft 23 55 can then be placed on the new roller die and replaced within the frame, thereby greatly simplifying the changing of the roller dies and making a strong and durable joint between the parts.

60 The lower gears of the intermeshing pairs of gears 22 are connected by gears 28. A large driving gear 29 is keyed on the opposite end of the shaft of a lower central roll from that upon which the gear 22 is attached. The driving gear 29 meshes in a

gear 30 on the auxiliary driving shaft 31 which shaft 31 also bears a gear 32 which meshes in a gear 33 on the main driving shaft 34, which main driving shaft has the pulleys 35 keyed thereon, a belt shifter 36 70 being provided for throwing the machine into and out of operation.

The pairs of roller dies 26 are arranged in series so as to gradually bend and shape the sheet metal strip 37 into the desired 75 shape. Many of the bends, however, are difficult to attain in the roller dies and are much more quickly and easily attained in fixed dies in which the tongues and grooved surfaces may be curved or even spiral in 80 form, as shown at 55 in Fig. 6, or 56 in Fig. 8, thus accomplishing a large amount of work in one fixed die. Accordingly, the roller dies and fixed dies are arranged alternately in series so that the sheet metal 85 strip is progressively shaped. The fixed edge dies 34 are also provided at the entrance between the first pair of roller dies so that the strip 37 is guided correctly into 90 said dies. The fixed shaping and bending and guiding dies 38 are generally provided one between each two pairs of rolls. The upper and lower rolls of the roller dies 26 are adjusted by the springs 20 and screws 21 so as to give the required opening 95 between the roller or the pressure upon the metal strip, the shape or contour of the rolls being varied so as to progressively bend the sheet metal.

The roller dies are of course necessary to 100 feed the sheet metal strip 37 through the fixed dies and the machine. There are also certain shaping manipulations of the sheet metal which can be better performed on the roller dies than on the fixed dies, as for example sharp corners and definite impressions, and there are other bends that can be better attained by the fixed dies. Hence the two coöperate together to attain the shaping and bending and guiding far better than 105 either one used alone. It is apparent that if the fixed dies were used by themselves a draw bench would be necessary to pull the stock through the dies, whereas in my construction the roller dies perform this office. 110

The fixed dies 38 are attached by means of screw-bolts across the space between the inner sides of the blocks 14 of the frames 12 and 13 so that the openings through said fixed dies are in line with the openings between the roller dies 26. The fixed dies are arranged in series with the roller dies to co-operate therewith; thus in the series of fixed dies shown in Figs. 4, 5, 6, 8 and 9, the first three fixed dies are closed so as to hold the 120 stock firmly in line and press it into the desired shape in order to form the channel 125 39 in the molding or frame side 40.

Thus the first two pairs of roller dies do not have the fixed die therebetween, being 130

only general forming rolls to start the metal into shape. The first fixed die 41, as shown in Fig. 4, has on its lower surface the general forming contours of the second pair of roller dies and has also the addition of the assisting roller 42 rotatively mounted within the die opening to aid the point of heaviest pressure so that the frictional draw of the sheet metal will not be so great as to be fairly prohibitive or so that the roller dies cannot feed the sheet metal strip 37 through the machine. The roller 42 also holds the last end of the strip 37 perfectly in line so that it is correctly formed. The inner sides of the opening in the die 41 are curved and shaped to continue the bending and shaping process started by the two first pairs of roller dies 26, and the central curve 43 is more pronounced to force the sheet metal up into the spool shaped roller 42 as it is held firmly in line by the inner sides of the fixed metal die.

The next pair of rollers 26 continues the shaping and bending process and the next fixed die 44 has the addition of a central tongue 45 which forces the sheet metal up against the spool shaped roller 46 which is practically the same as the roller 42 in die 41. The die 44 also has the groove 47 at one side to give clearance to the flanged edge 48 of the molding 40 and start the formation of the same, which formation is continued in the fourth pair of roller dies and still more perfectly shaped by the projecting tongue 49 on the next fixed die 50 of the series. This die also has a central tongue 51 which holds the groove 39 in shape and forms the sides more perfectly, preparing the nearly formed molding for the fifth pair of rolls which accomplishes much in perfecting the shape of the different parts. The fourth fixed die 52 of the series has the tongue but is an open-topped die, it being only necessary to hold the parts in perfect form to close up certain of the openings between the sheet metal walls preparatory to entering the fifth pair of roller dies 26 and the fifth fixed die 53, which practically finish the closing process, the last pair of roller dies only perfecting the drawing of the metal into line. The fixed die 53 has a rearwardly extending horn 57 which engages in the channel 58 of the adjacent edge portion of the metal strip and which inclines toward the opposite edge 59 for bending or moving the channel 58 over into contact with the opposite edge portion as the strip enters the last rollers, said rollers bending down the edge 59 and locking the edges together. The horn 57 extends rearwardly to coöperate with the last rollers in bending and clenching the edge 59 about the free edge of the channel 58 to form the flange 48, as shown in Fig. 26.

As hereinbefore stated, the larger part of

the bending and shaping of the sheet metal strip 37 is attained in the fixed dies rather than in the roller dies. This is made specially obvious when spiral bends have to be made in the shaping up of the sheet metal, as is so often the case. It is apparent that a single pair of roller dies cannot give a spiral bend but only one step in that spiral bend and that in order to give a spiral bend with roller dies a series of pairs must be employed, whereas in a fixed die the sides may be spirally curved or otherwise tongued and grooved so as to accomplish in one fixed die that which would take many pairs of roller dies in the bending of the sheet metal. The fixed die also will attain the shaping and bending necessary to close a molding far better than a pair of roller dies, that is, much more can be accomplished by a single fixed die than by one pair of roller dies, hence with roller dies to draw the stock or strip through the fixed dies and add a step in the process of shaping and bending the two forms of dies coöperate in a peculiarly helpful manner.

It is apparent from this general description of the operation of the machine that the fixed dies 38 perform a much larger portion of the work than the pairs of roller dies 26 when operated in combination therewith, also that the addition of the assisting rollers 42 or 46 to the fixed dies greatly aid in overcoming the frictional draw on the metal therethrough as well as the same in line. It would not depart from my invention to add additional rollers to the fixed dies should there be more than a single point of heavy frictional pressure of the sheet metal in the fixed die. Those portions of the fixed dies which receive the greatest wear are preferably faced with hardened steel plates so as to form the molding with the least wear on the dies and keep the dies in perfect form for a much greater length of time.

The shape of tubular molding of the frame side 40 is chosen as a representative molding showing some of the hardest problems presented in the drawing of sheet metal molding. It is apparent that open-sided sheet metal molding may be drawn in the same manner as the tubular molding.

I claim as new:

1. In a sheet metal bending and shaping machine, means for feeding a metal strip and bending it between its edges to provide a channel in one side adjacent the free edge portion thereof with which the free edge of the opposing side is to interlock, a pair of rollers for bending the latter edge over the channeled edge when the two edge portions are brought into contacting relation, and a fixed die having a horn extending therefrom transversely of the path of the strip to engage in the channel of the strip

for moving the adjacent free edge portion into contacting relation with the other edge portion of the strip for action thereon by said pair of rollers, said horn further serving to guide and hold the strip in its movement.

2. In a sheet metal shaping and bending machine, a pair of shaping roller dies, and a fixed guiding and shaping die arranged 10 adjacent the roller dies and consisting of a base block having an upwardly facing groove, a die section seated in the block groove, a bending and guiding section secured to the block on each side of the groove, 15 and a top plate connecting the bending and guiding sections and having a pair of bracket extensions depending between the bending and guiding sections and over the die section, and a roller journaled in the 20 bracket extensions.
3. In a sheet metal shaping and bending

machine, a fixed guiding and shaping die comprising a base block having a central upwardly facing cut-out portion formed with a bottom groove constituting a seat 2 for a die section, a die section engaged in said seat of the base block and a bending and guiding section on each side of the cut-out portion of the base block removably secured to the upper face of the latter, said bending and guiding sections opposing one another with their opposing edges converging toward one another, one of said edges being provided with a rib also extending in converging relation to the opposing edge. 3

In testimony whereof I have affixed my signature in the presence of two witnesses.

FRANK S. VERNON.

Witnesses:
